DESIGN FOR A HYDRANT

Elmer M. Deters, Davenport, Iowa, assignor to
Red Jacket Manufacturing Co., Davenport,
Iowa, a corporation of Iowa

Application May 4, 1945, Serial No. 119,390

Term of patent 7 years

(Cl. D65—1)

To all whom it may concern:

Be it known that I, Elmer M. Deters, a citizen of the United States, residing at Davenport, in the county of Scott and State of Iowa, have invented a new, original, and ornamental Design for a Hydrant, of which the following is a specification, reference being had to the accompanying drawing, forming part thereof.

In the drawing:

Figure 1 is a side elevational view of a hydrant showing my new design, the opposite side being a mirror image of that shown in Figure 1;

Fig. 2 is a side elevational view of the dominant portions of the design on an enlarged scale;

Fig. 3 is a top plan view thereof;
Fig. 4 is an end elevational view, and
Fig. 5 is an end elevational view of the end opposite that shown in Fig. 4.

The dominant features of the design reside in the portions shown in full lines.

The pipe portions are omitted in Figs. 3, 4, and 5 for convenience of illustration.

I claim:

The ornamental design for a hydrant, substantially as shown and described.

ELMER M. DETERS.
